UNITED STATES PATENT OFFICE.

HERBERT THOMAS GIRDLESTONE AND JAMES REST, OF LONDON, ENGLAND.

HAND TOOL FOR COMPRESSING VALVE SPRINGS AND FOR ANALOGOUS PURPOSES.

Application filed March 29, 1926, Serial No. 98,125, and in Great Britain January 20, 1926.

This invention relates to hand tools of the prising, compressing or cramp type, and has for its object to provide a tool of simple and compact, but nevertheless efficient, construction.

A tool embodying the invention comprises a frame, a member movably supported by the frame and adapted to engage and disengage or grip and release the article to be operated upon, and mechanism for actuating the movable member and locking it in the operative position, such mechanism being operable from a point distant from the article in connection with which the tool is destined to be used.

We will now describe, by way of example and with reference to the accompanying drawings, one form of tool, constructed in accordance with the invention, specially applicable for compressing the springs of the valves of internal combustion engines in situ.

Of the aforesaid drawings:

Fig. 1 is a side elevation representing the tool in the operative position relatively to a valve indicated in dot-and-dash lines, the right-hand and left-hand sides being, for distinction, designated the "front" and the "rear" respectively;

Fig. 2 is a corresponding front elevation of the tool;

Fig. 3 is a rear elevation thereof; and

Fig. 4 is a sectional plan of the tool, the section being taken on the line 4—4 in Fig. 1.

According to this example, to constitute the aforesaid frame, we construct a member *a* with a rectangular cavity *b* formed by the front and rear sides *c* and *d* and the ends *e* and *f*. To the bottom of the frame *a*, and at the rear side thereof, we fix a member *g* to constitute a foot or abutment in the use of the tool. This foot or abutment *g* may be of a jaw or any desired structure, the former being illustrated at *h*; and, as is also illustrated, it may have a depending retaining or guiding flange *i* at its outer edge. The frame rear side *d*, from this member *g* to the top, is cut away or left open in the making, centrally and vertically, to provide a slot *j*. Towards the bottom of the frame *a*, and in the vicinity of the foot or abutment *g*, the ends *e* and *f* are cut away to furnish openings or slots *k* and *l*; as shown, the slot *l* is shorter than the slot *k* for the purpose that will be explained presently. The

front side *c* is formed with an opening *m*, and, although not shown, the rear side *d* may be formed with a coincident opening or simply a recess.

A member *o* is reciprocably associated with the frame *a* to constitute the before-mentioned movable member. This member *o* comprises a head *p*, a body *q*, and a neck *r* connecting the two. The head *p* is shaped to conform with the cavity *b* of the frame *a*, and the neck *r* with the slot *j* in the rear side *d* thereof, while the body *q* is of a horseshoe structure with a marginal upright ledge *s*. The member *o* is assembled with the frame *a* with the head *p* reposing in the cavity *b* and the neck *r* in the slot *j*, hence the body *q* projects from the rear *d* of the frame *a*.

The aforesaid actuating and locking mechanism comprising a spindle *t* of any appropriate length such as to present unimpeded distant operation. The spindle *t*, near the rear end, is provided with a heart-shaped-like cam *u* for coacting with the lower end of the head *p* of the movable member *o*. The cam *u* is formed with a hump *v* for interacting with the slots *k* and *l* in the ends *e* and *f* of the frame *a* as hereafter described, the lengths of the slots *k* and *l* relatively to the circumferential length of the cam *u* being such that the shorter slot *l* functions to impeditingly contact at the top and bottom with the cam *u* in its travel in the upward direction, while the longer slot *k* permits of unrestricted travel in the opposite direction. The distant or front end of the spindle *t* is fitted with a tommy-bar *w*. This mechanism *t* and *u* is assembled with the frame *a* and the movable member *o* with the cam *u* located in the frame cavity *b* below the head *p* of the movable member *o* and in alignment with the slots *k* and *l* in the frame ends *e* and *f*, the spindle *t* passing through the opening *m* in the front *c* of the frame *a* in which opening *m* a journal *n* fits, and its extreme end being tightly fitted in the cam *u* and riveted over the rear side thereof. Thus the spindle *t* is rotatably mounted in the frame *a*. When an opening or recess is provided in the rear side *d* complementary to the opening *m*, the extreme end of the spindle *t* is passed through the cam *u* and journaled therein, the cam being suitably secured to the spindle *t*.

Briefly, the mode of use and operation of the tool—assuming means of any appro-

priate kind have been applied, if required, to the valve to hold it stationary—are as follows:

The tool is suitably positioned, that is, for instance, with the frame *a*, through the agency of its foot or abutment *g*, standing upon or co-acting with an appropriate support, such as the crank case, the cylinder base, or, as exemplified, with its jaw *h* and flange *i* embracing the tappet end or nut *w*, and with the movable member *o* in engagement with the collar *y*, or it may be the pin on the valve stem *z*, the bifurcated structure of the head *p* of the member *o* admitting of ready assembly and disassembly and the upright ledge *s* assuring engagement. Then the shaft *t* is turned by the tommy-bar *w* whereupon, through the agency of the cam *u*, the movable member *o* is lifted with a straight-line motion whereby the valve spring is compressed, this condition being maintained or locked by the interengagement of the hump *v* of the cam *u* with the slot *l* in the end *f* of the frame *a* and thereby admitting of the manipulation of the requisite valve components, the hump *v* of the cam *u* projecting through the slot *l* and contactually and limitarily bearing at the top and bottom upon the corresponding ends of the slot *l*. The movable or reciprocable member *o* may be restored by hand to its operative position relatively to the cam *u* which is returned to its initial position by turning the spindle *t*, the slot *h* giving the requisite clearance.

It will be evident from the foregoing that the cam device *u* may be substituted by mechanical equivalents, such as a rack and pinion; and that the structural details of the tool may be variously modified without departing from the essential features comprising a reciprocable engaging and disengaging or gripping and releasing member *o* actuatable by a distantly-operable spindle *t* through interposed interengaging elements, and a frame or support *d* for the member *o*, the spindle *t* and the allied parts.

What we claim and desire to secure by Letters Patent is:

1. A hand tool of the type described comprising, in combination, a frame consisting of a member having a rectangular cavity

formed by the sides and the ends and having at the bottom of the rear side a member constituting a foot or abutment in the use of the tool, said rear side having a slot running centrally and vertically from said foot or abutment to the top, and said ends having slots; a member movably supported by said frame and composed of a head, a body and a neck, said head and neck, respectively, conforming to said frame-cavity and said rear-side frame-slot, and on assembly reposing therein with said body projecting from the rear of said frame; an actuating and locking mechanism including a spindle journaled in said frame, a cam provided on said spindle and located in said cavity below said head of said movable member and in alignment with said slots in said frame ends.

2. A hand tool of the type described comprising, in combination, a frame consisting of a member having a rectangular cavity formed by the sides and the ends and having at the bottom rear side a member constituting a foot or abutment of jaw-structure, said rear side having a slot running centrally and vertically from said foot or abutment to the top, and said ends having openings or slots of unequal lengths; a member reciprocably supported by said frame and composed of a head, a body and a neck, said head and neck respectively conforming to said cavity in said frame and said slot in its said rear side and on assembly reposing therein with said body projecting from the rear of said frame, said projecting body being of a horse-shoe-like structure with a marginal upright ledge; and actuating and locking mechanism for said reciprocable member, said mechanism including a spindle journaled in said member, a cam provided on said spindle located in said frame-cavity below said head of said reciprocable member and in alignment with said slots in said frame ends, said cam co-operating with the shorter of said slots to lock the parts in the operative position.

In testimony whereof, we affix our signatures.

HERBERT THOMAS GIRDLESTONE.
JAMES REST.
